CLAIM

The ornamental design for a portable tire inflator, as shown and described.

DESCRIPTION

FIG. 1 is a front perspective view of a portable tire inflator, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view of area 9 in FIG. 1; and,
FIG. 10 is an enlarged detail view of area 10 in FIG. 1.

The broken lines in the drawings illustrate the portions of the
portable tire inflator, which form no part of the claimed
design.

The dash-dot-dash broken lines encircling the enlarged
views are for annotative purposes only and form no part of
the claim thereof.
